GUN CHARGER

Harry C. Grant, Jr., New York, N. Y., assignor to
 Specialties Development Corporation, Bloom-
 field, N. J., a corporation of New Jersey

Application November 14, 1941, Serial No. 419,053

8 Claims. (Cl. 89--1)

1

The present invention relates to automatic machine guns and the like, and more particularly to devices, known as gun chargers, for initiating the operation of a gun charging mechanism which normally is operated by the recoil resulting from the explosion of cartridges.

In automatic machine guns, for example, of the "Browning" type, release of the firing pin, either mechanically or electrically, fires a cartridge in the chamber of the barrel of the gun. The resulting recoil causes a bolt mechanism or charging mechanism to move backward to withdraw the exploded or fired cartridge case and, at the same time, to present a succeeding cartridge on a cartridge feed belt adapted to be fed into the chamber. After the bolt mechanism has been fully retracted, it returns to the firing position and in the course of its return stroke ejects the empty or fired cartridge case and feeds the succeeding cartridge into the chamber. While the firing pin is released, the gun fires when the bolt returns to the full forward position. If no trouble develops, the cycle of operation of the charging mechanism is repeated at a rate of between about 400 and 1000 shots per minute.

Once the gun has been loaded, firing should be automatic unless any one of a number of possible difficulties occurs. For example, a shell may fail to explode or may fail to develop a recoil force sufficient to move the bolt mechanism through the shell ejecting and loading cycle. Also, the charging mechanism may fail to extract the cartridge from the belt or a shell may jam in the barrel and resist removal on the first attempt. In addition, any one of the many elements of the bolt or charging mechanism may fail momentarily to perform its designed function and prevent the ejecting and loading cycle from being properly performed. In the event that the bolt or charging mechanism fails to function properly for any of the foregoing reasons, it is necessary to pull the bolt mechanism fully backward and then release it to complete the ejecting and reloading operation normally carried out by the gun itself after it has once been fired.

Heretofore, devices known as gun chargers have been employed for mechanically actuating the charging mechanism in response to failure of the gun to continue firing. None of these devices has been found fully satisfactory because of the complexity of design, unreliability of performance and relatively long delay occasioned before putting the gun into action again.

The present invention aims to provide an improved, practical, and reliable gun charging de-

2

vice which is accurately controlled, can stand rough usage and is adapted to return the gun to firing action in a minimum period of time.

An object of the present invention is to provide an improved gun charger which is light in weight and occupies a minimum amount of space.

Another object is to provide a gun charger having a minimum number of mechanical parts.

Another object is to provide a gun charger adapted to be mounted on either side of a machine gun, as may be decided in the field or prior to the installation of the guns in airplanes, tanks or other craft.

Another object is to provide a gun charger which is readily adjustable to compensate for variance in the stroke of the guns, whereby the gun charger may be transferred from one gun to another.

Another object is to provide a gun charger having a minimum number of parts which are in operation while the gun is firing normally.

Another object is to provide a gun charger adapted to be operated by a high pressure fluid medium and apply a force of a sufficient magnitude to initiate the movement of the bolt or charging mechanism.

Another object is to provide a detecting mechanism adapted to be used in connection with gun chargers, which is inactive during the normal motion of the operating mechanism of the gun and is operative in response to the lack of such normal motion.

Another object is to provide an accurate detecting mechanism for gun chargers and the like which can withstand shock and vibrations without getting out of adjustment or repair.

Another object is to provide an electrically operated detecting mechanism comprising a minimum number of parts, electrical connections and wiring circuits.

Another object is to provide a detecting mechanism for gun chargers which operates in response to failure of the gun to fire regardless of the position of the bolt or charging mechanism when stoppage occurs.

Another object is to provide a gun charger adapted to operate the bolt or charging mechanism through at least one complete cycle of operation.

Another object is to provide a gun charger having a detecting mechanism adapted to put the gun charger back into operation within substantially the same period of time required for one cycle of operation of the gun, whereby the gun remains out of action a minimum length of time.

A further object is to provide a gun charger having a detecting mechanism adapted to be cut out of operation when the gun charger initiates operation of the bolt or charging mechanism and adapted to remain out of operation until the gun is restored to normal firing operation.

Other and further objects, not specifically enumerated above, will be apparent when described in greater detail in connection with the accompanying drawings, wherein:

Figure 1 is a diagrammatic side view of a machine gun having a gun charger attached thereto.

Figure 2 is a schematic view of the essential operating parts of a gun charger, illustrating an embodiment of the invention.

Figure 3 is a wiring diagram of the electrical circuits of a gun charger, in accordance with the invention.

Figures 4 and 5 are simplified wiring diagrams, illustrating the operation of the detecting mechanism of the gun charger.

Figure 6 is a simplified wiring diagram, similar to Figures 4 and 5, illustrating the detecting mechanism cut out of operation while the gun charger moves the bolt or charging mechanism.

Figures 7, 8 and 9 are simplified wiring diagrams, illustrating a modified circuit for the detecting mechanism of the gun charger.

In accordance with the invention, it has been found that the foregoing objects may be accomplished by providing a detecting and initiating device, suitable for machine guns and other purposes, having electrical detecting and controlling means which is operable in response to a current pulse of a predetermined minimum time interval, and which is not affected by current pulses of less than the minimum time interval.

In a practical embodiment, illustrative of the invention, such a device, generally, may comprise a circuit supplied with a continuous current from a direct current source; relay means or the like connected in the circuit, the relay means being constructed and arranged to be actuated by a current pulse of a predetermined minimum time interval in either direction, but being unaffected by current pulses of less than the minimum time interval; and means associated with the bolt or charging mechanism of a machine gun for periodically interrupting the continuity of a portion of the circuit, whereby the relay means is subjected to current pulses of less than the minimum time interval during normal movement of the bolt or charging mechanism. Thus the relay means, during continuous firing of the gun, is not affected by the periodically interrupted current or current pulses of less than the minimum time interval, but upon failure of normal movement of the bolt or charging mechanism, the interruption of the current ceases for a sufficient duration to permit current of a substantially continuous character or a current pulse of the minimum time interval to energize the relay means and effect operation thereof. The invention further contemplates the use of such a detecting and controlling device in combination with a fluid pressure operated ram for mechanically moving the charging mechanism through its operating cycle. In addition, the gun charger may be provided with means for rendering the detecting and controlling device ineffective when the ram commences to function and may be provided with other cooperating devices and improvements which will be pointed out more particularly hereinafter.

Referring to the drawings, and more particu-

larly to Figure 1, there is shown a machine gun, for example, of the "Browning" type which, generally, comprises a barrel assembly 10 and a bolt mechanism or charging mechanism (not shown), which is located in a housing or casing 11. The charging mechanism is of the usual design and includes a number of slidably movable or reciprocating parts which are moved rearwardly by the recoil resulting from the explosion of cartridges and which are moved forwardly by a return spring or the like. During reciprocation of these parts, the operating cycle of the gun is carried out. This cycle comprises removing a cartridge from the cartridge belt and inserting it into the chamber, firing the cartridge, withdrawing the fired cartridge from the chamber and ejecting the empty cartridge case from the housing 11. Since the construction and operation of such a charging mechanism is well known to those skilled in the art, a detailed illustration and description is not believed to be necessary.

In the event the normal operating or firing cycle of the gun is interrupted and firing ceases, the gun must be recharged or recocked before it can be put in operation again. To accomplish this, a gun charger 12, suitably encased, may be attached to either side of the gun housing 11 and may be operatively connected to the bolt or charging mechanism by a bolt or stud member 14 which extends through an elongated slot 15 in the housing 11 and is movable with the reciprocating parts of the charging mechanism. The gun charger 12 preferably is operated by a fluid pressure medium, such as high pressure carbon dioxide, air or any suitable gas stored in a pressure vessel 16 and adapted to be supplied to the gun charger by a hose or tube 17. A cable 18 containing electrical conductors for the electrical devices of the gun charger is attached to one end of the gun charger.

In Figure 2, the essential operating parts of the gun charger are illustrated schematically. The reciprocating bolt or stud member 14 of the gun charging mechanism is shown adjacent and in the path of a ram 19, or the like, adapted to engage the member 14 and move it towards the left along the slot 15, that is, rearwardly with respect to the gun, in the event the gun ceases firing during operation thereof. The ram 19 comprises a cylinder 20 and a slidable member 21 adapted to be telescoped in the cylinder 20. The member 21 has a piston 22 at one end and a ramming head 24 at the other end for moving the bolt or stud member 14.

The ramming head 24 has a recessed end face 25 for engaging an adjustable stop 26 threaded through the bolt or stud 14. The stop 26 may be utilized to accurately determine the distance the bolt or stud 14 and the slidable parts of the charging mechanism can be moved rearwardly by the ram. The ramming head may be slidably mounted on a pair of spaced apart parallel guide tubes or rods 27 which extend respectively through guide apertures in outwardly extending lugs or ears 29 carried by the head 24. One of the lugs 29 of the head 24 may have a downwardly depending extension 30 provided with a pair of arms 31 and 32 which extend in a direction parallel to the movement of the head and are adapted to operate devices described herein-after.

The slidable ram member 21, preferably, is moved out of the cylinder 20 by supplying a fluid pressure medium in back of the piston 22 and is returned to the position shown in Figure 2 by

suitable springs 34. A valve 35 is utilized to control the admission and the exhaust of the pressure medium to and from the cylinder. This valve may comprise a body having a chamber therein; a valve seat 36 in communication with the chamber and an inlet port 37 connected to the pressure medium supply hose 17; a second valve seat 38 in communication with the chamber and an exhaust port 39; a valve member 40 in the chamber; and a conduit 41 leading from the chamber to the cylinder 20. When the valve member 40 abuts the seat 36, the inlet port 37 is shut off and the exhaust port 39 is open to enable pressure medium in the cylinder 20 to escape, whereby the springs 34 may rapidly return the slideable member 21 to the position shown in Figure 2. When the valve member 40 is moved towards the right and abuts the seat 39, the exhaust port is closed and the inlet port is opened to admit pressure medium to the cylinder. The valve member 40 is provided with a stem 42 extending outwardly through the valve body and adapted to be engaged by a suitable valve controlling device about to be described.

The device for controlling the valve may comprise an arm or finger 44, for engaging the valve stem 42 which is mounted on one end of a slideable rod 45 extending through one of the tubular guides 27; a lever 46 pivoted at 47 and having the other end of the rod 45 connected thereto at 48; and a spring operated device connected to the other end of the lever 46. The spring operated device may comprise a tubular collar 50 pivotally connected to the lever 46 at 51; a slideable bar or rod 52 extending through the collar 50 and limited for sliding movement with respect thereto by a flange 54; and a cylindrical helical spring 55 which is telescoped about the rod 52 and is compressed between a flange 56 adjacent one end of the rod 52 and the collar 50. The end of the rod 52 adjacent the flange 56 has one end of a tension spring 57 attached thereto and the other end of the spring is secured to a suitable fixed point at 59. The other end of the rod 52 is provided with a projection, tooth, or dog 60 adapted to be engaged by a projection 61 on a latching lever 62 pivotally mounted at 64.

When the projections 60 and 61 are in engagement, the spring 55 is compressively loaded and bears against the collar 50 to swing the lever 46 in a direction to slide the rod 45 into a position whereby the finger 44 holds the valve stem 42 to cause the valve member 40 to close the inlet port 37. The projections 60 and 61 may be unlatched by a solenoid 65 or other suitable device to be actuated when movement of the ram is desired. When the projections 60 and 61 are unlatched, the spring 55 expands, and the rod 52 slides within the collar 50 to a position where the flange 54 abuts the collar 50 and the spring 55 has no effect on the lever 46. The spring 57 then pulls the rod 52 to swing the lever 46 into the position, indicated by the broken line (denoting the longitudinal axis of the lever), and the lever moves the rod 45 to enable the finger 44 to release the valve stem 42. Movement of the rod 45 may be further assisted by a spring 66 attached to the end thereof or to the finger 44. Preferably, the lever 46 is latched in this position by a latch member 67 carried by the lever and having a projection 69 adapted to engage a fixed latch projection 70.

When the stem 42 is released, the pressure of the pressure medium moves the valve member 40 away from the seat 36 and the pressure me-

dium is admitted to the cylinder 20 to move the ram member 21 outwardly. The head 24 of the slideable ram member, as it moves along its path, engages the stop 26 of the bolt or stud 14 wherever it may be along the slot 15, and moves the bolt 14 and the reciprocating parts of the charging mechanism to their extreme rearward or leftward position.

When the ramming head approaches its rear-most position, it is desired to shut off the supply of pressure medium and exhaust the cylinder. This is accomplished by the arm 31 which engages, for example, the flange 56 of the rod 52 and pushes the rod through the collar 50 to reload the spring 55 and cause the projections 60 and 61 to reengage. Upon further movement of the head 24, the slightly shorter arm 32 comes in contact with the latch member 67 and releases the projection 69 from the projection 70. This enables the spring 55 to swing the lever 46 into its initial position, whereby the rod 45 is moved to cause the finger 44 to operate the valve stem 42 which in turn causes the valve member to close the inlet port 37 and open the exhaust port 39. The sudden exhaust of the fluid pressure medium from the cylinder enables the springs 34, which are relatively strong, to return the ram member 21 and its associated parts to their forward position.

It will be understood that, while an illustrative embodiment of a device or devices for controlling the mechanical operation of the ram has been described, other devices suitable for accomplishing this purpose may be utilized and that the present invention is not intended to be limited to the illustrative control means just described.

The present invention, as illustrated in the embodiment thereof, is more particularly concerned with a method and apparatus for detecting when the reciprocating movement of the stud or bolt 14 and its associated parts is interrupted, is slowed down in some manner or ceases, due to failure of the gun to fire and recoil. These detecting means then control the operation of the solenoid 65 which permits mechanical action of the ram and its control devices. These detecting means may be structurally associated with the reciprocating bolt 14 to detect lack of motion thereof by a current pulsing means such as an interrupter or alternator operated, actuated, driven or otherwise associated with the reciprocating parts of the gun charging mechanism.

In Figure 2 of the drawings a current interrupter is illustrated as a fixed elongated commutator bar or frame 75 on which is mounted a series of alternately arranged electrical conducting members 76 and non-conducting members 77. A slideable frame 79 is mounted on the guide rods or tubes 27 and is attached to the stud 14 for movement therewith. The frame 79 carries a brush or wiper 80 for alternately contacting the members 76 and 77 while reciprocating with respect thereto. The conducting members 76 and the brush 80 are operatively connected in an electrical circuit about to be described. The members 76 and 77 preferably are of substantially equal effective length whereby the period of flow of current and the period of interruption of current are of a substantially equal duration of time. Any suitable number of elements, members or contacts 76 and 77 may be provided. Instead of using a fixed interrupter bar 75, as illustrated, it will be understood that the stud 14 could carry any suitable linkage for driving a rotatable interrupter, commutator or alternator adapted to

be contacted by a stationary brush, without departing from the scope of the invention.

Referring to Figure 3 of the drawings, there is shown a wiring diagram of a preferred electrical detecting and operating circuit or "brain." This circuit is illustrated as a modified bridge type circuit, and will be described in detail hereinafter. The circuit shown is particularly adapted for machine guns installed in airplanes, tanks or other craft wherein the gun may be operated locally or from a remote location. Generally, to accomplish this the electrical devices of the circuit are arranged in three groups designated as the control panel, the relay panel and the gun charger.

The control panel has mounted thereon, a pilot light 85 adapted to be illuminated when the gun charger ram 19 is operating; a switch 86 having a "safety," "off" and "firing" position; and a switch 87 for effecting operation of the gun charger at the will of the gunner or operator. A firing or trigger switch 89 is operatively associated with the control panel, and may be located adjacent the gun or at a remote location where the gunner or operator may centrally control the firing of one or more machine guns. An electrical heater 90 may be provided for the vessel 16 containing the pressure medium to prevent the pressure from dropping below a desired minimum when the vessel is exposed to very low temperatures, such as may be encountered at high altitudes. The heater circuit may lead to the control panel and preferably has a thermostat 91 therein which is operative in response to temperatures at which the heater 90 is desired to operate. A source of direct current is supplied by a line 92, conventionally indicated as having a positive polarity. The negative pole of the source of current (not shown) may be suitably grounded and the various circuits may be respectively grounded at desired points to complete the paths through which current may flow.

The relay panel has mounted thereon three resistance elements 94A, 94B and 94C, the purpose of which will be described hereinafter; a relay 95 adapted to be operated by continuous current and unaffected by rapidly interrupted current; and a second relay 96 adapted to be operated by the relay 95 to close a circuit adapted to supply current to the pressure medium valve controlling solenoid 65. If desired the relay 96 may be omitted by providing the relay 95 with contacts for closing the solenoid circuit.

The gun charger has associated therewith the current interrupter, indicated by the interrupter bar 75 and the brush 80; a resistance element 94D; a switch 97 for cutting out the detecting circuit when the ram 19 is operated; and a switch 99 movable into a position for closing the pilot light circuit responsive to the operation of the ram. The solenoid 65 for controlling the pressure medium valve 35 also may be associated with the gun charger and a circuit may pass through the gun charger housing for energizing a firing pin solenoid 100 associated with the firing mechanism of the gun.

The electrical circuits, illustrated in Figure 3, will now be described. The switch 86 is of the double pole double throw type having a center "off" position. The switch comprises a pair of poles 101 and 102; a pair of contacts or terminals 104 and 105 adapted to be engaged by the poles 101 and 102, respectively, when the switch is in a "safety" position; and a pair of contacts or terminals 106 and 107 adapted to be engaged by the poles 101 and 102, respectively, when the switch

is in a "firing" position. The pole 101 is electrically connected to the current supply line 92 by a wire 109, and the terminals 104 and 106 are electrically connected to each other by a wire 110 and to a wire 111 through which current is adapted to pass when the switch 86 is in either of its closed positions.

The wire 111 is connected to a wire 112 which is connected to one terminal of the thermostatically responsive switch 91. The other terminal of the switch 91 is connected to one terminal of the heater 90, which has its other terminal grounded at 114. The wire 111 is also connected to a wire 115 which is connected to one terminal of the manually operable switch 87 and the other terminal of the switch 87 is connected by a wire 116 to one terminal of the pressure medium valve controlling solenoid 65, which has its other terminal grounded at 117. The wire 111 also is connected to one terminal of the pilot light 85 by a wire 118 and the other terminal of the pilot light 85 is connected to one terminal of the pilot light operating switch 99 by a wire 120. The other terminal of the switch 99 is grounded at 121.

The pole 102 of the switch 86 is adapted to contact the switch terminals 105 and 107. In the circuit shown, the terminal 105 is not electrically connected because it is superfluous, but the terminal 107 is connected to the firing circuit by a wire 122, as described hereinafter. The pole 102 is connected to one terminal of the firing or trigger switch 89 by a wire 124 and the other terminal of the switch 89 is connected to the supply line 92, whereby when the switch 86 is in firing position and the trigger switch 89 is closed, current flows through the firing circuit by way of the wire 122.

The firing circuit includes a single pole double throw switch 125 which is associated with the relay 96 and normally is in position to close the firing circuit, as shown in Figure 3. The switch 125 when in this position, is adapted to permit current to pass from the wire 122 to a wire 126 connected to one terminal of the firing pin solenoid 100, which has its other terminal grounded at 127. When the relay 96 is operated, the switch 125 is adapted to be moved into its other position to permit current to flow from the wire 122 to a wire 128 connected to the wire 116 leading to the pressure medium valve controlling solenoid 65.

A preferred method for supplying interrupted current to the relay during the normal operation of the gun and continuous current during stoppage or slowing down of the gun charging mechanism may comprise connecting the relay into a circuit including a current supply and an interrupter, in such a manner, that it is normally subject to a rapidly interrupted current by which it is not affected, and that it is subject to a continuous current when the charging mechanism has stopped for a given period.

A preferred circuit for carrying out this method of detecting the lack of reciprocating movement of the gun charging mechanism and for initiating operation of the gun charging ram will now be described in detail. This circuit is illustrated in Figure 3 and is illustrated in simplified form in Figures 4, 5 and 6. Generally, this circuit comprises the current interrupter 75; the brush 80 moved by the reciprocating parts of the gun charging mechanism; the resistance elements 94A, 94B, 94C and 94D; the relay 95; and the cut-out switch 97 adapted to render the circuit ineffective during operation of the ram 19. Electrical energy is adapted to be supplied to the circuit from the source of direct current 92 con-

nected through the switch 86 and the firing or trigger switch 89, when in firing position, to the wire 122 which in turn is connected to a wire 130. The path of the current which may pass through the circuit is completed by grounding the brush 80 at 131 and the resistance element 94C at 132 (Figure 3) or by electrically connecting the brush 80 by a wire 134 to the grounding connection at 132 (Figures 4, 5 and 6).

In the detecting circuit the resistance elements 94A and 94B each have one terminal connected to the current supply wire 130. These elements have substantially the same electrical resistance, to provide an electrically balanced circuit under certain conditions of operation, which will be described hereafter. The other terminal of the element 94A is connected to one terminal of the element 94D by a wire 135 and the other terminal of the element 94D is connected to a wire 136 which is connected to all of the conducting members 76 of the interrupter 75. The other end of the element 94B is connected to one terminal of the element 94C which has its other terminal grounded at 132. The elements 94C and 94D have substantially the same electrical resistance for the reasons described hereafter.

In effect, and as illustrated more particularly in Figures 4, 5 and 6, the elements B and C and the elements A and D, respectively, are connected in series. The respective pairs of elements provide, in effect, parallel circuits leading from the wire 130 to the grounding connections at 132. The relay 95 is connected across these "parallel circuits" by connecting one terminal of the relay 95 to the wire 135 or the connection between the elements 94A and 94D and connecting the other terminal of the relay 95 to the connection between the elements B and C, indicated at 137.

The relay 95, as previously explained, is of the type which is adapted to be operated by continuous current flowing in either direction, for a predetermined period but is not affected by current which alternates its direction of flow or is interrupted at a frequency higher than a predetermined frequency. Such a relay may be of the so-called "time delay" type in which a heavy copper ring encircles the core of the relay. When current starts to flow through the coil of such a relay, in either direction, a counter voltage is induced by the short-circuiting copper ring, retarding the build-up of magnetic flux and therefore retarding the operation of the relay. When the current has established itself, however, the copper short-circuiting ring has no effect and the relay operates in the normal manner. The only effect of this ring is to delay the relay operation for a fraction of a second. Thus when alternating current of a sufficiently high frequency is applied, the relay is not affected and will not operate because the direction of the current is being reversed so rapidly that the magnetic flux does not have an opportunity to build up.

It has been found that a relay, known as a direct current, series, slow releasing type relay may be utilized. Preferably this relay has an operating time of about .004 to .25 second and a releasing time of about .020 to .350 second. Such a relay is illustrated on page 8 of Catalogue 4071-B, published February 1940, by American Automatic Electric Sales Company, Chicago, Illinois. Since such relays are generally known and are commercially available, a detailed description of the construction thereof is not believed to be necessary. It will be understood, that while a re-

lay of the foregoing character is preferred, other devices having similar electrical characteristics may be employed.

The relay 95 may be provided with a single pole, single throw switch 139 (Figure 3) which normally is in open position and is adapted to be closed by the operation of the relay 95 to close a circuit leading from wire 122 through the coil of the relay 95 to the grounding connection at 140. Thus, when the switch 139 is closed, current is supplied to the relay 95 to operate the switch 125 which closes the pressure medium valve controlling sole-noid circuit to effect operation of the ram 19.

The relay 95, when connected in the circuit just described, is normally supplied with alternating or rapidly reversing current while the gun charging mechanism is reciprocating or is operating to load and fire the gun at its normal speed. The alternation of the direction of flow of the current is accomplished by the circuit, shown in Figures 3, 4, 5 and 6, and the interrupter 75 or other suitable device therein in the following manner.

When the brush 80 contacts any one of the current conducting elements 76 (Figure 4), current from the wire 130 divides and flows through the resistance elements 94B and 94C to the grounding connection at 132, as indicated by the arrows a. The divided portion of the current flows through the resistance element 94A, the wire 135, the switch 97 (normally closed), the wire 136, one of the conducting elements 76, brush 80, and wire 134 to the grounding connection as indicated by the arrows b. The resistance to the flow of current in the path of the arrows a will be greater than the resistance to the flow of current in the path of the arrows b, whereby a portion of the current in path a will divide out at 137 and pass through the relay 95 in the direction indicated by arrow c. It will be understood that the resistance characteristics of the relay coil are such that they will not impede the flow of current in direction c.

When the brush 80 is moved out of contact with any of the conducting elements 76 and contacts any one of the non-conducting elements 77 or is in a position between the contacts 76 (Figure 5), current flows through the circuit as follows. The current divides at the wire 130 and a portion thereof flows through the resistance elements 94B and 94C to the grounding connection 132 as indicated by the arrows a. The other portion of the current flows through the resistance element 94a as, indicated by the arrows b and through the coil of the relay 95 to 137 as, indicated by the arrow d, because the circuit leading through the interrupter 75 is broken.

The direction d, as will be noted, is opposite to the direction c, and the direction in which the current flows is rapidly alternated by the rapid movement of the brush 80 from a circuit closing to circuit opening position. Thus, if a sufficient number of conducting elements 76 and alternately arranged non-conducting elements 77 are provided in the interrupter and the interrupter brush 80 is reciprocated at a rate of 400 to 1000 strokes per minute the direction of the current will be alternately reversed at a rate at which the relay 95 will not be operated. For example, if the frequency of current reversal is of a magnitude at which current flows in either direction for a period of time, shorter than the time required by the relay to build up magnetic flux, the relay will not be affected. The relay will be operated only when the brush 80 stops moving or slows down to an extent where the frequency of the current

reversals is relatively low. The latter condition would indicate that the gun is not firing properly. In the event the brush stops while in contact with a conducting element 76, direct current will flow through the relay coil in direction *c* (Figure 4). If the brush stops while out of contact with an element 76, direct current will flow through the relay coil in direction *d* (Figure 5).

The operation of the cut-out switch 97 is illustrated in Figure 6. In the event the detecting devices initiate operation of the ram 19, the ramming head 24 or a member carried by the head may mechanically engage the switch 97 upon initial movement of the ramming head 24 and move it out of its normal position shown in Figures 4 and 5 and into the position shown in Figure 6, whereupon the switch 97 opens the connection between the wires 135 and 136 and connects the wire 136 to the grounding point 141.

If the brush 80 is out of contact with a conducting element 76 of the interrupter, the current will divide at 130 and a portion will flow through the resistance elements 94B and 94C to the grounding connection 132 and the other portion of the current will flow through the resistance element 94A, the wire 135, the resistance element 94D, the wire 136 and the switch 97 to the grounding point 141. Since the resistance of element 94A is equal to element 94B, and the resistance of element 94C is equal to element 94D, the sum of the resistance of elements 94A and 94D is equal to the sum of the resistance of elements 94B and 94C. Therefore, the same proportion of currents flows in paths *a* and *b*, whereby the two paths are balanced and no current flows through the relay 95. Thus when this condition prevails, the relay is insensitive and is not operated. The switch 97 is designed to return by itself or to be returned by the ramming head to its initial or normal inactive position when the ram is moved into its normal or at rest position, as indicated in Figure 2.

In the event the ram is operated to move the cut-out switch 97 out of its normal position while the brush contacts one of the conducting elements 76, the foregoing result is accomplished in substantially the same manner. The only difference now is that the current in the path *b* may flow to either of the grounding connections 132 and 141 to complete the circuit. The circuits indicated by the paths *a* and *b* then are again balanced and no current is supplied to the relay 95.

In operation, the gun charger 12 is attached to either side of the machine gun housing 11, the pressure medium vessel 16 is connected to valve 35 by the hose 17 and the electrical circuits are connected to a source of electric energy, while the main switch 86 is in its "off" position. When the switch is in this position, accidental closing of the manually operable charging switch 87 or the trigger switch 89 will not effect operation of the gun charger or firing of the gun. After the gun and the gun charger is set up for action, either in the field, in an airplane or other craft, the switch 86 is placed in its "safety" position. This enables the gun to be charged by closing the manually operable charging switch 87, but accidental closing of the trigger switch 89 will not fire the gun. Shortly prior to the time it is desired to fire the gun, the switch 87 is closed to charge the gun and the switch 89 is placed in its "firing" position, whereby the gun may be fired by closing the trigger or firing switch 89 to energize the firing pin solenoid 100.

Once the gun commences firing and the trigger switch 89 is held in closed position by the gunner or operator, the gun continues to fire and the charging mechanism goes through its cycle of operation, namely, feeding, firing and ejecting cartridges. During the operation of the charging mechanism, the current interrupter 75 is operated and the direct current supplied to the detecting devices is converted into substantially rapidly interrupted or alternating current with respect to the relay 95. While the current is thus alternated or interrupted, the continuous current responsive relay 95 is unaffected and does not operate. However, if normal movement of the reciprocating parts of the gun charging mechanism should cease, the current through the relay becomes sufficiently continuous to cause actuation of the relay. Within a fraction of a second, the relay 95 is operated to close the switch 139, whereby current flows through the auxiliary relay 96 to operate the switch 125. The switch 125 cuts out the source of current supplied to the firing pin solenoid 100 and connects this source of current to the pressure medium valve controlling solenoid 65.

The solenoid 65 is immediately effective to release the latch and lever mechanism, illustrated in Figure 2, which in turn operates the valve to admit pressure medium to the cylinder 20 of the ram. The ram is then operated to mechanically move the gun charging mechanism through its operating cycle to put the gun in action again. As the ram is operated, the cut-out switch 97 is moved into the position in which it prevents the flow of current through the detecting relay 95 (Figure 6). Also, the pilot switch 99 is closed so that current flows through the pilot light which indicates to the gunner that the automatic gun charger is in operation. When the ram returns to its normal inactive position and the gun is restored to normal firing the pilot switch 99 and the cut-out switch 97 return to their initial positions under the influence of suitable resilient means (not shown). As the gun resumes firing the solenoids of the relays 95 and 96 become de-energized to permit the switches 139 and 125 to return to their initial positions under the influence of resilient means usually associated with relays of the type employed.

In Figures 7, 8 and 9 a modified circuit is illustrated, for interrupting the current for the detecting mechanism by alternating the direction thereof. The interrupter 75 comprises a series of conducting elements or contacts 76 and 76', alternately arranged and spaced apart a short distance by insulation, if desired. The contacts 76 are connected by a wire 145 to one terminal of the source of direct current indicated at 130, and the contacts 76' are connected by a wire 146 and a resistance element 194C to the other terminal of the source of current indicated at 132. A slider or brush 80 rides upon a conducting bar or slide 83 connected by a wire 147 to one terminal of the relay 95. A resistance element 194A has one terminal connected at 130 to the source of current and has its other terminal connected at 137 to one terminal of a resistance element 194B, which has its other terminal connected at 132 to the other pole of the source of current. The other terminal of the relay is connected at 137.

The relay 95 operates only in response to direct or continuous current of sufficient duration in either direction and the interrupter 75, in conjunction with the circuit as shown, is adapted to effect a rapid reversal of the direct current sup-

plied while the gun is firing and the brush 80 is being reciprocated. The direction of the current through the relay is changed as follows.

When the brush 80 contacts one of the elements 76, as shown in Figure 7, a portion of the current flows through resistance elements 194A and 194B, as indicated by arrows *a*. Another portion of the current flows through wire 145, contact 76, brush 80, bar 83, and wire 147 to the relay 95 in the direction as indicated by arrows *b*.

When the brush 80 contacts one of the elements 76' as shown in Figure 8, the current flows through resistance element 194A and a portion of the current flows through resistance element 194B, as indicated by arrows *a*. The current divides at 137 and a portion thereof flows through the relay 95, wire 147, bar 83, brush 80, contact 76', wire 146 and resistance element 194C to the pole 132 of the source of current as indicated by arrows *a'*.

In the event the gun ceases firing and the brush stops in an intermediate position where it contacts both an element 76 and 76', as shown in Figure 9, a portion of the current flows through resistance elements 194A and 194B. Another portion of the current flows through wire 145 to the interrupter 75 where it divides and a portion flows through wire 147 and the relay 95 in the direction of arrow *b* and the other portion of the divided current flows through the wire 146 and resistance element 194C to the current connection 132, as indicated by the arrow *b'*. The resistance element 194C prevents a direct short circuit and preferably has a resistance slightly greater than the resistance element 194B so that the circuit is unbalanced and current flows through the relay 95.

During the normal firing of the gun the direction of the current is alternately reversed as noted in connection with Figures 7 and 8. If the gun should cease firing and the brush stops in any one of the positions shown in Figures 7, 8 and 9, current will flow continuously in the direction indicated.

From the foregoing description it will be seen that the present invention provides an improved gun charger and improved method of operation. The gun charger detecting devices are adapted for machine guns having a relatively high firing speed and quickly detect a failure of operation and return the gun to firing operation in a minimum period of time. Machine guns equipped with gun chargers in accordance with the invention are adapted to be put in action again in a split second and the effective firing of the gun is not materially decreased even under adverse conditions, whereby the gunner is not endangered by being subjected to enemy fire without being able to return fire. The parts of the gun charger are rugged in construction and are adapted to withstand any rough usage to which they may be subjected.

While my invention has been described in connection with a gun charger for automatic machine guns, it will be understood that the principles of my invention may be applied to other mechanisms where it is desired to detect the slowing down or stopping of any mass or parts normally intended to be in motion. For example, a detecting device embodying my invention may be utilized in connection with electrical, pneumatic or hydraulic motors, internal combustion or steam engines, or other mechanisms or devices having parts moving in a circular, linear or curvilinear path.

While my invention resides in certain principles of construction and operation which have been illustrated and described in connection with the accompanying drawings, it will be apparent to those skilled in the art that the invention may be embodied in other forms of construction and modes of operation without departing in any manner from the spirit and scope of the invention, and I therefore do not wish to be strictly limited to the disclosure, but rather to the scope of the appended claims.

I claim:

1. In a gun charger for a machine gun having a reciprocating member, the combination with 15 said reciprocating member of a normally inactive recharging mechanism for operating the reciprocating member, an electrical control device constructed and arranged to be actuated by a current pulse of a predetermined minimum time in-

20 terval for rendering said recharging mechanism operative, an energizing circuit for said control device, and current pulsing means in said circuit adapted to be driven by said reciprocating member, said pulsing means being constructed and 25 arranged to successively energize said control device for intervals less than said minimum time interval during the normal operation of said reciprocating member and to energize said control device for said time interval for rendering said recharging mechanism operative upon failure of normal operation of said reciprocating member.

2. In the combination of claim 1, means operated by said recharging mechanism upon movement thereof for rendering said pulsing means 35 ineffective to energize said control device.

3. In the combination of claim 1, said current pulsing means including a commutator, and a brush adapted to be connected to said reciprocating member for cooperation with said commutator.

4. In the combination of claim 1, said current pulsing means including a commutator, a brush adapted to be connected to said reciprocating member for cooperation with said commutator, and switch means constructed and arranged for rendering said commutator ineffective when said recharging mechanism is operated.

5. In the combination of claim 1, said energizing circuit comprising two portions, said control device being connected across said portions, said current pulsing means including a current interrupter actuated by said reciprocating member connected in one of said circuit portions.

6. In the combination of claim 1, said energizing circuit comprising a bridge having four resistance elements, the total resistance in a pair of adjacent elements being equal to the total resistance in the other pair of adjacent elements, said control device being connected across said pairs of elements and said pulsing means including a current interrupter adapted to be actuated by said reciprocating member for interrupting said bridge at a common junction of said pairs of elements, whereby said control device is energized.

7. In a gun charger for a machine gun having a reciprocating bolt, the combination with said bolt of a normally inactive ram for operating the bolt, an electrical control device including a relay constructed and arranged to be actuated by a current pulse of a predetermined minimum time interval for rendering said ram operative, an energizing circuit for said relay, and current pulsing means in said circuit adapted to be driven by said bolt, said pulsing means being constructed

15

and arranged to successively energize said relay for intervals less than said minimum time interval during the normal operation of said bolt and to energize said relay for said time interval for rendering said ram operative upon failure of normal operation of said bolt.

8. In a gun charger for a machine gun having a reciprocating bolt, the combination with said bolt of a normally inactive ram for operating the bolt, an electrical control device including a relay constructed and arranged to be actuated by a current pulse of a predetermined minimum time interval for rendering said ram operative, an energizing circuit for said relay, current pulsing

5
10

16

means in said circuit adapted to be driven by said bolt, said pulsing means being constructed and arranged to successively energize said relay for intervals less than said minimum time interval during the normal operation of said bolt and to energize said relay for said time interval for rendering said ram operative upon failure of normal operation of said bolt, and a switch in said circuit constructed and arranged to be operated by said ram upon initial movement thereof for rendering said pulsing means ineffective to energize said relay during operation of said ram.

HARRY C. GRANT, JR.
